United States Patent Office

Des. 200,406
Patented Feb. 23, 1965

200,406

BRASSIERE

Edward E. Astor, Fort Lee, N.J., assignor to International
Latex Corporation, Dover, Del., a corporation of Delaware

Filed Mar. 25, 1963, Ser. No. 74,096

Term of patent 14 years

(Cl. D20—4)

Des. 200,406

FIG. 2.

FIG. 1 is a plan view of a brassiere showing my new design;

FIG. 2 is a plan view of another embodiment of the design shown in FIG. 1; and

FIG. 3 is a plan view of a further embodiment of the design shown in FIG. 1.

I claim:

The ornamental design for a brassiere, as shown and described.
